United States Patent Office

Des. 201,939
Patented Aug. 10, 1965

201,939

SPECIMEN COLLECTOR

Inez B. Weiler and William H. Weiler, both of
1660 Long St., Santa Clara, Calif.

Filed Mar. 9, 1964, Ser. No. 78,919

Term of patent 14 years

(Cl. D83—1)

Fig. 2

Fig. 4

Fig. 3

Fig. 5.

Fig. 1

Fig. 6.

FIG. 1 is a perspective view of a specimen collector showing our new design, the broken lines are shown for illustrative purposes only;

FIG. 2 is a top plan view thereof;

FIG. 3 is a side elevation thereof;

FIG. 4 is an end elevation as seen from the right of FIG. 2;

FIG. 5 is an end elevation as seen from the left of FIG. 3; and

FIG. 6 is a bottom plan view as seen from below in FIG. 3 and at slightly larger scale.

We claim:

The ornamental design for a specimen collector, as shown and described.
